UNITED STATES PATENT OFFICE

REX ADAMS, OF NEW YORK, N. Y.

DESIGN FOR A SCORING DISK FOR RING AND HORSE SHOE GAME

Application filed January 4, 1932. Serial No. 42,363. Term of patent 7 years.

To all whom it may concern:

Be it known that I, REX ADAMS, a citizen of the United States, residing at New York, in the county of New York and State of New York, have invented a new, original, and ornamental Design for a Scoring Disk for Ring and Horse Shoe Game, of which the following is a specification, reference being had to the accompanying drawings, forming part thereof.

Fig. 1 is a face view of a scoring disk for ring and horse shoe game, showing my new design.

Fig. 2 is an edge view of the same.

Fig. 3 is a perspective view of the same.

I claim:—

The ornamental design for a scoring disk for ring and horse shoe game, as shown.

In testimony whereof I have affixed my signature.

REX ADAMS,
